(57) **CLAIM**

The ornamental design for the “vehicle wheel”, as shown and described.

DESCRIPTION

FIG. 1 is a perspective view of the vehicle wheel showing my new design;

FIG. 2 is a front elevational view thereof; and,

FIG. 3 is an end elevational view thereof taken along the line 3—3 of FIG. 2.

The broken line showing of environment is for illustrative purposes only and forms no part of the claimed design.
